UNITED STATES PATENT OFFICE.

CARL STEFFEN, OF VIENNA, AUSTRIA-HUNGARY.

APPARATUS FOR REFINING LOAF SUGAR IN MOLDS.

SPECIFICATION forming part of Letters Patent No. 443,549, dated December 30, 1890.

Application filed August 10, 1889. Serial No. 320,346. (No model.)

To all whom it may concern:

Be it known that I, CARL STEFFEN, of the city of Vienna, Austria-Hungary, have invented certain new and useful Improvements 5 in Apparatus for Refining Loaf Sugar in the Molds, of which the following is a specification.

My invention relates to the construction of an apparatus for refining loaf or lump sugar 10 in the molds, in which the sugar can be refined either as a congealed crystalline mass or in granular pulpy form.

The refining process is carried out by employing a saturated solution of pure sugar, 15 (the so-called "lixiviating-fluid" or "cleare,") and is effected in a systematic manner—that is, in such manner that the molds for the loaves or sugar to be treated or refined are connected so as to form a battery in form of 20 a column in which the single-loaf forms are superposed or placed one above the other and snugly fitted together, the supply-pipe for the lixiviating or refining fluid being connected to the uppermost loaf-mold while the lowermost mold is arranged above a reservoir for receiving the spent fluid or is connected to a suitable trough or tube for leading off the same. The lixiviating or refining fluid becomes more and more impure the farther it 25 descends down the battery or loaf molds, in consequence of the sirup which it washes off the sugar-crystals, while the sugar in the upper mold will be perfectly refined or freed from sirup when a given quantity of the lixiviating-fluid or cleare has passed through 30 the same. As soon as the operation has reached this stage the uppermost mold is removed and the battery again completed by inserting a freshly-charged mold in the lower 35 part of the battery. In order to produce a snug contact between the loaf-molds forming the column-like battery and to be able to remove the finished loaf with its form and insert a fresh-charged loaf-mold in the battery, 40 I employ a hydraulic press or other suitable raising device and also a retaining device for the upper molds for facilitating the insertion of a fresh-charged mold at the lower end of the battery. As soon as the requisite quantity of lixiviating-fluid has passed through 45 the oldest or uppermost mold of the battery the remaining fluid is pressed forward or

downward in the battery, so that the crystalline mass in the uppermost form is comparatively dry before its removal.

If a hard crystalline mass is treated, the same is simply charged into the mold; but if a granular pulpy mass is used the tips of the loaf-molds can be provided with a sieve, as represented in the accompanying drawings, 55 in which—

Figure 1 is a vertical section of the column-like battery-or loaf-molds for treating sugar, the lower part being represented in elevation. Figs. 2, 3, and 4 are sections of the tips of the 60 loaf-molds with sieves of varied construction on an enlarged scale.

The loaf-molds *a* are provided with hermetically-closed lids or covers *b*, which are pressed onto the molds by clutch-bolts *c*, or in other 70 suitable manner. An opening is bored through the center of each of the covers, and this opening surrounded with an annular flange *d* for receiving an india-rubber or other suitable packing *e*, so as to produce an air-tight joint 75 between the perforated tip of the upper mold and the cover to the next following mold, whereas the cover of the uppermost mold is packed in like manner to receive the nozzle 80 of the supply-pipe *f* for the lixiviating-fluid, the tip of the lowermost mold being fitted into a cup-like extension of the receiver *g*, which is in connection with a trough *h* or tube for leading off the lixiviating-fluid from the last mold, which said fluid has become 85 very impure from the sirup washed from the sugar-crystals in the molds. This trough *h* is formed in or mounted on the head-plate *i* of a hydraulic piston *k*, which when raised will press the various molds into close air-tight connection with each other. In order to exchange 90 the molds, as is requisite in the process of systematic lixiviation, or, in other words, to be able to remove the upper mold and insert a freshly-charged mold at the lower end of the 95 battery, each mold is provided near its apex with an annular flange *l*, each of said flanges, in order to prevent the lateral movement of the molds forming the battery, being connected by bolts *m* to the lid of the next lower 100 mold. These annular flanges *l* rest on the pawls *n*, or an equivalent device, when the upper part of the battery requires to be held up, so as to enable a freshly-charged mold to

be inserted at the lower end of the said battery. The annular flanges *l* can be fixed to the molds, or the molds may be placed in the same before the said molds are employed for forming the battery.

If granular pulpy sugar mass is to be lixiviated, a sieve *o* is placed in each of the molds, said sieve being flat, Fig. 2, conical or cylindrical, Fig. 3, or of other suitable form.

10 The compressed air for pressing or forcing the lixiviating-fluid through the molds after the supply of fluid has been cut off is fed in through the tube or pipe *p*. The supply-pipe *f* runs, preferably, through the massive upper 15 plate *s* of the frame-work to the battery, of which *r* are the columns or standards, which also serve as guides for the head or plate *i* of the hydraulic piston.

As already mentioned, it is by no means 20 necessary that hydraulic devices be used, as any appropriate raising and lowering device can be employed, and it will furthermore be evident to all versed in the art that the form and details of my improved apparatus may 25 be modified in various ways without departing from the nature of my invention.

The operation of my improved apparatus is as follows: As soon as the battery has been formed by placing a number of forms or 30 molds one above the other, so as to form a column-like battery, and the same have been pressed into snug contact with each other by the hydraulic piston or other raising device, the cock or valve to the supply-pipe for the 35 lixiviating-fluid is opened and the said fluid pressed through the mass of sugar in the mold forming the battery. As soon as a sufficient quantity of the lixiviating-fluid, which has in passing through the battery become 40 very impure, and which corresponds with the quantity of pure fluid required for perfectly refining the sugar in the uppermost mold, has passed off from the lowest mold, the supply 45 of lixiviating-fluid is cut off and the valve of the compressed-air pipe opened, so that the compressed air will press the fluid in the molds downward and out of the battery, whereupon the molds forming the battery are lowered. The upper mold, which contains 50 perfectly-refined sugar, is now removed, the molds forming the battery again raised, so

that the second mold of the first operation will be the first mold in the second operation, and so on, the lower mold being held up by means of its annular flange *l* and the pawls 55 or arms *n*, a freshly-charged mold with unrefined sugar inserted, and the piston of the hydraulic or other device raised until snug air-tight contact is obtained between the various members of the battery. The operation 60 of systematic lixiviation can now be repeated, as before described.

Having now particularly described my said invention and in what manner the same is to be carried into effect, what I claim is— 65

1. In an apparatus for refining sugar, a series of separable molds having perforated tips arranged one over the other and provided with perforated covers and means for pressing the latter onto the molds, a pipe for the 70 admission of lixiviating-fluid and a pipe for compressed air, and a lifting-machine supporting the lowermost mold, substantially as set forth.

2. In an apparatus for refining sugar in 75 the mold, a series of separable molds having perforated tips and perforated covers arranged one above the other and connected together, devices *n* for temporarily supporting the molds above the lowermost, and a lifting 80 machine or press supporting the lowermost mold, substantially as set forth.

3. The combination of the series of molds *a*, having perforated tips and provided with perforated covers *b* and packings *e*, the latter being each adapted to receive the perforated tip of the mold next above, substantially 85 as set forth.

4. The combination of the series of molds *a*, having perforated tips and perforated covers and adapted to be fitted together in a vertical series, said molds being provided with sieves *o* within their tips, substantially 90 as set forth.

In witness whereof I have hereunto signed 95 my name in the presence of two subscribing witnesses.

CARL STEFFEN.
